UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

KNIFE GUARD FOR SLICING MACHINES

Application filed June 4, 1930. Serial No. 398,448.

My invention relates to a slicing machine having a rotary knife and relates particularly to a knife guard for such slicing machine. One object of my invention is to provide a guard which shall cover the forward side of the exposed cutting arc of a rotary knife. Another object is the provision of such a guard which may be applied to a work carriage traveling across the face of said knife. Another object is the provision of such a guard which shall cover or guard the cutting edge of the knife when the carriage reaches the end of its cutting excursion and when the work has been carried past the cutting edge of the knife. Another object is the provision of a combined guarding and supporting member which shall combine the function of guarding the edge of the knife when the carriage has been moved past it and the function of holding the work against retrograde movement in relation to the cutting edge of the knife when the carriage is being thrust past the knife on its cutting excursion. Another object is the provision of guard means which shall have a combined warning and protective function in relation to the hand of the operator when the operator is thrusting the pusher plate across the carriage toward the cutting plane of the knife during the cutting reciprocation of the carriage. Other objects will appear from time to time in the course of the specification and claims.

I illustrate my invention more or less diagrammatically in the accompanying drawings, wherein—

Figure 1 is an elevation of the front of the slicing machine;

Figure 2 is a partial end elevation;

Figure 3 is a partial plan view;

Figure 4 is a front elevation illustrating my device applied to a different type of slicing machine; and

Figure 5 is a plan view of the structure shown in Figure 4.

Like parts are indicated by like symbols throughout the specification and drawings.

Referring first to the form of Figures 1 to 3, A generally indicates any suitable slic-

ing machine base with the ground engaging supports A¹.

B indicates a gauge plate mounted on the supporting and actuating structure B¹, the details of which do not of themselves form part of the present invention.

C generally illustrates a rotary knife mounted on the shaft C¹, which may be actuated as by the pulley C², the belt C³, and the drive pulley C⁴. It will be understood, that any suitable means, for example, an electric motor, may be mounted to drive the knife through the above described driving connection. C⁵ illustrates any suitable guard plate for the front of the knife, the guard and gauge plates being indicated as lying in generally vertical, generally parallel planes. The axis of the shaft C¹ may be tilted somewhat to bring the cutting arc of the knife, as indicated at C⁶, forwardly into or in front of the plane of the guard plate.

D generally indicates the carriage mounted on the track D¹ of cylindrical cross-section. Depending from the carriage is a portion D² with the flanges D³ which are positioned on opposite sides of a guide track D⁴. Pivotally mounted on the carriage D is a work supporting structure which includes the plate E, the hinged supports E¹ therefor, and any suitable pivot pin or pins E². E³ indicates an adjusting link slotted as at E⁴ engaged by the locking member E⁵ on the carriage.

Mounted for movement across the plate E is the pusher plate G with the handle G¹ secured to its rear as by the bracket G². The opposite end of the handle is connected, as by the member G³ with the sleeve G⁴ which is slidable along the pin G⁵ which is mounted on the projection G⁶ on one of the hinge members E¹.

Positioned along the left edge of the plate E, as shown in Figure 1, the edge which is remote from the cutting arc of the knife when the plate is in the full line position of Figure 1, I illustrate an upstanding work engaging flange H. Adjacent the cutting plane it is upwardly expanded as shown at H¹ in Figure 2. The separately expanded portion terminates closely adjacent the face

of the gauge plate. The gauge plate is shown in Figure 2 as bowed, the edge of the member H^1 being bowed to conform thereto. The function of this bowing is to conform to the contour of the cutting arc C^6 of the knife, which is somewhat bowed from the vertical, owing to the tilting of the knife axis above alluded to. Associated with the guard H^1 is an additional guard member H^2 , which may be secured to H^1 . It is shown in Figure 1 as terminating in a generally arcuate edge roughly conforming to the cutting arc of the knife when the parts are in the dotted line position in which they are shown in Figure 1. It will be noted that the member G^3 is somewhat arched, in order to clear the top of the flange H , and is positioned in such relation to the sleeve G^4 that it cannot engage the edge of the upstanding flange H^1 , since the inner edge of the sleeve G^4 engages the portion G^6 , as shown in Figure 3, which may serve as a stop.

Referring to the form of Figures 4 and 5 I illustrate more or less conventionally a type of slicing machine in which the meat carriage I is reciprocated along a track I^1 on the base I^2 in response to rotation of the fly wheel I^3 with its manual handle I^4 . The manual wheel is merely illustrative of any suitable driving means for actuating the carriage I but it will be understood that in the device shown in Figures 4 and 5 each reciprocation of the carriage I automatically results in a forward movement of an independent carrier K toward the cutting plane of the knife. The details of this driving mechanism do not of themselves form part of the present invention but I illustrate in association with a carrier K the worm K^1 actuated by the tooth wheel K^2 through the ratchet K^3 . K^4 indicates an upstanding support upon which is mounted the work engaging clamp K^5 , whereby the work is clamped upon the carrier K . This type of machine is in contrast to the manual or non-automatic type as shown in Figures 1 to 3 and indicates the applicability to the automatic type of guards corresponding to the members H^1 H^2 of Figures 1 and 3. I indicate, mounted adjacent the edge of the carriage I the guard L which lies in a plane generally parallel with the cutting plane. Associated with it may be an extension L^1 , corresponding to H^1 , and lying in a plane generally perpendicular to the plane of the guard L . These guard members, shown in Figures 4 and 5 as a unitary structure, may be bolted to the edge of the carriage I as at L^2 .

It will be realized that whereas I have described and shown a practical and operative device, nevertheless many changes might be made in the size, shape, number and disposition of parts without departing

from the spirit of my invention. I therefore wish my description and claims to be taken as in a broad sense illustrative and diagrammatic rather than as limiting me to my specific showing.

The use and operation of my invention are as follows:

The safety of the operator is of course a prime feature of importance in a slicing machine. In the old hand driven slicing machines where the knife was rotated at relatively slight speed and where it rotated only in response to the manual actuation of the operator, the risk of damage was relatively slight. In the form of my device shown in Figures 1 to 3 an extremely sharp rotary knife is motor driven at a speed of a thousand R. P. M. or more. Not only is the sharp knife driven at such a speed dangerous, but its presence tends to have an intimidating effect upon an operator. Hence the importance of shielding it. When the gauge plate B is set to zero, as in Figure 3, it masks the edge of the cutting arc of the knife, the rest of the knife being concealed behind the guard plate C^5 or contained within the frame and housing of the device. But when the gauge plate is withdrawn, particularly when thick slices are being cut, the cutting arc is inevitably exposed. I have therefore provided the guard H^2 which, when the carriage D reaches the end of its cutting excursion, overlies and shields the cutting arc from the carriage side. This position of the guard is shown in dotted line in Figure 1 and if an operator wishes to interrupt the slicing operation without returning the gauge plate to neutral he can safely leave the machine by merely leaving the carriage at the extremity of the cutting excursion, with the guard H^2 overlying the cutting arc.

In the form of Figures 1 to 3 the operator may employ the member G^1 as a handle or the member G^4 , or the pin G^5 , if the pusher plate is not employed. A frequent method of operation is for the operator to grasp either the pin G^5 or the sleeve G^4 , with one or more fingers extending over the flange H and in contact with the work. Thus with one hand the operator not only reciprocates the carriage but also controls the pusher plate G , if he is using it, or directly engages the work with his fingers, if he is not using the pusher plate. As the successive slices are taken the hand of the operator advances closer and closer to the cutting plane and the guard portion H^1 is eventually engaged by his fingers. It has the double function of positively preventing so close an approach of his fingers as will cause risk of cutting, and of warning him, in case his eyes are not on the work, of his close approach to the cutting edge. Finally, the positioning of the handle and guide pin G^5

on the opposite side of the flange H^1 from the work grips the hand of the operator in a relatively safe position as regards the cutting edge of the knife, and, when a number of slices have been taken from the work, tends to keep the hand of the operator in the shelter of the guard members H^1 and H^2 .

A further function of the guard member H^1 is to engage and support the work as it is moved against the cutting edge of the knife and to prevent the work from receding from the knife or from binding frictionally on the gauge plate. This tends to obviate the formation of tails on the work and makes for an evener slice. Also, by reducing the frictional drag and by positively forcing the work forward, it eases the frictional contact of knife and work and tends to reduce frictional heating of the knife and consequent larding of the work. This is particularly important in connection with slicing fat meats such as ham, bacon, salt pork and the like.

I claim:

1. In association with a slicing machine including a knife and means for actuating it and a work supporting member and means for guiding it across the face of the knife, and an outwardly bowed gauge plate, a guard, lying in a plane generally parallel with and closely adjacent the cutting plane, adapted to mask the cutting edge of the knife from the work support side at the termination of the cutting excursion of the work support, the guard being bowed to conform generally to the bowing of the gauge plate.

2. In association with a slicing machine including a knife and means for actuating it and a work supporting member and means for guiding it across the face of the knife, a guard, lying in a plane generally parallel with and closely adjacent the cutting plane, adapted to mask the cutting edge of the knife from the work support side at the termination of the cutting excursion of the work support, said guard having a generally straight edge generally perpendicular to the face of the work support, and an additional guard member, intersecting said first mentioned guard along said straight edge and extending outwardly away from the cutting plane.

3. In association with a slicing machine including a knife and means for actuating it and a work support movable across the face of the knife, a work engaging flange, generally perpendicular to the cutting plane, extending along the edge of the work support remote from the cutting edge of the knife when the work support is in initial position prior to the cutting excursion, a guard adapted to mask the cutting edge of the knife from the work support side at the termination of the cutting excursion of the

work support, said guard lying generally parallel with and closely adjacent the cutting plane and including a generally straight edge upwardly extending from and aligned with the face of the work engaging flange, and an additional guard member, extending outwardly from said straight edge lying in the general plane of the work engaging flange.

4. In association with a slicing machine including a knife and means for actuating it and a work support movable across the face of the knife, a handle positioned adjacent the edge of the work support remote from the cutting edge of the knife when the work support is in initial position prior to the cutting excursion, a guard element adapted to mask the cutting edge of the knife from the work support side at the termination of the cutting excursion of the work support, and an additional guard element, extending outwardly from said first guard element, away from the cutting plane, interposed between the work support and the handle.

5. In association with a slicing machine including a knife and means for actuating it and a work support movable across the face of the knife, a handle positioned adjacent the edge of the work support remote from the cutting edge of the knife when the work support is in initial position prior to the cutting excursion, a guard element adapted to mask the cutting edge of the knife from the work support side at the termination of the cutting excursion of the work support, and an additional guard element, extending outwardly from said first guard element, away from the cutting plane, interposed between the work support and the handle, and a work engaging abutment or flange upwardly projecting from the work support along the edge adjacent the handle.

6. In association with a slicing machine including a knife and means for actuating it and a work support movable across the face of the knife, a handle positioned adjacent the edge of the work support remote from the cutting edge of the knife when the work support is in initial position prior to the cutting excursion, a guard element adapted to mask the cutting edge of the knife from the work support side at the termination of the cutting excursion of the work support, and an additional guard element, extending outwardly from said first guard element, away from the cutting plane, interposed between the work support and the handle, and a work engaging abutment or flange upwardly projecting from the work support along the edge adjacent the handle, this abutment and the last mentioned guard element lying in substantially the same plane.

7. In association with a slicing machine

including a knife and means for actuating it and a work support movable across the face of the knife, the edge of the work support lying closely adjacent the cutting plane of the knife, a guard adapted to mask the cutting edge of the knife from the work support side at the termination of the cutting excursion of the work support, said guard including a member positioned at the forward corner of the work support remote from the knife when the work support is in initial position prior to the cutting excursion and including a plurality of generally plane elements, one lying in a plane generally parallel with and closely adjacent the cutting plane and underlying in a plane generally perpendicular to the cutting plane.

8. In association with a slicing machine including a knife and means for actuating it and a work support movable across the face of the knife, the edge of the work support lying closely adjacent the cutting plane of the knife, a guard member mounted adjacent the forward edge of said support on the side of the support farthest from the cutting edge of the knife when the support is in initial position prior to its cutting excursion, said guard member including one element lying in a plane generally parallel with the cutting plane of the knife and another element at an angle thereto.

9. In association with a slicing machine including a knife and means for actuating it and a work support movable across the face of the knife, the edge of the work support lying closely adjacent the cutting plane of the knife, a guard member mounted adjacent the forward edge of said support on the side of the support farthest from the cutting edge of the knife when the support is in initial position prior to its cutting excursion, said guard member including one element lying in a plane generally parallel with the cutting plane of the knife and another element at an angle thereto, and a handle positioned adjacent said guard member and between said elements.

10. In association with a slicing machine including a knife and means for actuating it, a carriage and means for guiding it across the face of the knife, a work engaging flange mounted on the edge of the carriage remote from the cutting edge of the knife at the initiation of the excursion of the carriage, a pusher plate mounted on the carriage and means for guiding it for movement across the carriage toward the cutting plane of the knife, including a pin positioned on the side of said work engaging flange away from the carriage, and a guard, associated with said work engaging flange, adapted to mask the cutting edge of the knife at the termination of the cutting excursion of the carriage, said guard lying in a plane generally parallel with the cutting

plane and at right angles to the plane of said flange, said guard extending to a substantially greater height than the height of the flange, the portion of the flange adjacent its junction of said guard being upwardly extended to conform in height to the abutting portion of said guard.

11. In association with a slicing machine including a knife and means for actuating it, a work supporting carriage and means for guiding it across the face and past the cutting edge of the knife, a guard positioned upon said carriage and movable therewith, lying in a plane generally parallel with and closely adjacent the cutting plane, said guard being adapted to mask the cutting edge of the knife from the work supporting side at the termination of the cutting excursion of the work support, and a second guard, generally perpendicular to said first mentioned guard and generally perpendicular to the cutting plane, the two guards intersecting, the intersection defining a generally straight edge generally perpendicular to the work supporting face of the carriage and generally parallel with and closely adjacent the cutting plane and a handle positioned adjacent the intersection of the two guards, on the side of said intersection away from the knife.

12. In association with a slicing machine including a knife and means for actuating it, a work supporting carriage and means for guiding it across the face and past the cutting edge of the knife, a guard positioned upon said carriage and movable therewith, lying in a plane generally parallel with and closely adjacent the cutting plane, said guard being adapted to mask the cutting edge of the knife from the work supporting side at the termination of the cutting excursion of the work support, and a second guard, generally perpendicular to said first mentioned guard and generally perpendicular to the cutting plane, two guards intersecting, the intersection defining a generally straight edge generally perpendicular to the work supporting face of the carriage and generally parallel with and closely adjacent the cutting plane, and a handle for said carriage, said handle being positioned rearwardly of said first mentioned guard, and being positioned relatively closely adjacent said second guard, at a level substantially below the top of said second guard, and on the side of said second guard opposite to the cutting edge of the knife when the carriage is at the beginning of the cutting stroke.

13. In association with a slicing machine including a knife and means for actuating it, a work supporting carriage and means for guiding it across the face and past the cutting edge of the knife, a guard positioned upon said carriage and movable therewith,

lying in a plane generally parallel with and closely adjacent the cutting plane, said guard being adapted to mask the cutting edge of the knife from the work supporting side at the termination of the cutting excursion of the work support, and a second guard, generally perpendicular to said first mentioned guard and generally perpendicular to the cutting plane, the two guards intersecting, the intersection defining a generally straight edge generally perpendicular to the work supporting face of the carriage and generally parallel with and closely adjacent the cutting plane, and a guide member positioned upon said carriage, said guide being positioned rearwardly of said first mentioned guard, and being positioned relatively closely adjacent said second guard, at a level substantially below the top of said second guard, a handle member slidable along said guide and a lateral extension therefrom, a pusher plate mounted upon said lateral extension, overlying and slidable across the work supporting face of the carriage, said lateral extension lying to the rear of said second guard when the pusher plate is advanced to its closest proximity to the cutting plane.

14. In association with a slicing machine including a knife and means for actuating it, a work supporting carriage and means for guiding it across the face and past the cutting edge of the knife, a guard positioned upon said carriage and movable therewith, lying in a plane generally parallel with and closely adjacent the cutting plane, said guard being adapted to overlie the cutting edge of the knife on the work supporting side at the termination of the cutting excursion of the work support, said guard being mounted upon said carriage adjacent the edge of the carriage remote from the cutting edge of the knife when the carriage is at the beginning of the cutting excursion, the carriage being provided with a handle portion associated with the same edge of the carriage, said handle portion being positioned to the rear of the said guard, the guard extending downwardly beneath the level of the handle a distance greater than the normal reach of a finger of the hand of an operator grasping the handle.

Signed at Indianapolis county of Marion and State of Indiana, this 5th day of June, 1929.

WILLIAM J. CAMPBELL.
